UNITED STATES PATENT OFFICE.

GEORGE W. MASCORD, OF BARNES, LONDON, ENGLAND.

INKING APPARATUS OF PRINTING-PRESSES.

1,254,338.

Specification of Letters Patent.

Patented Jan. 22, 1918.

Application filed July 20, 1915. Serial No. 40,921.

To all whom it may concern:

Be it known that I, GEORGE WILLIAM MASCORD, a subject of the King of Great Britain and Ireland, residing at 5 The Crescent, Barnes, London, S. W., England, have invented certain new and useful Improvements Relating to the Inking Apparatus of Printing-Presses, of which the following is a specification.

10 This invention relates to the inking apparatus of printing presses and has for its object to insure greater uniformity and more effective and flexible control in the application and distribution of ink.

15 In rotary printing presses the application of ink on starting and when stopping is frequently considerably less than that applied during the normal running of the press, owing to the flexibility of the duct blade and to the fact that during slow rotation of the ink duct roller on starting and stopping, the film of ink applied is thinner, while the movement of the duct roller is slower, so that in the result, the pages 20 printed by the press during the period of starting and speeding up as well as during the period of stopping or slowing down are faintly printed.

25 The invention has for its object to avoid this result, and according to the invention I provide means whereby the movement of the inking mechanism may be adjusted not to fall below a certain predetermined speed, so as thus to insure the adequate and automatic application of ink at periods of starting or speeding up and slowing down and stopping the press. The arrangement is such that the normal working of the press 30 is not interfered with as the supplementary feed is automatically put into or out of 35 operation at desired periods, as the press either speeds up or slows down.

40 According to the invention I may provide separate motors for the operation of the respective inking mechanisms of the press and I may provide the electric controller of the main motor of the press with contacts by 45 which the motors of the inking mechanisms may operate even although current is cut off 50 from the main driving motor of the press.

Or again, I may according to the invention provide the inking mechanisms of the press separately operated by gear and by a motor common to a number of inking mechanisms or to all the inking mechanisms of the press, the respective mechanisms being

caused to operate in synchronism by suitable connecting gear.

It will thus be understood that by reason of the fact that the inking mechanism is 60 operable from an independent motor, it is possible for the ink supply to be varied from a minimum to a maximum during the period of running of the press as may be required, and in addition that when starting 65 the press an adequate supply of ink may be provided by first setting the inking mechanism into operation.

The invention comprises the construction 70 which is hereinafter described.

The invention is illustrated in the accompanying drawings in which—

Figure 1 represents in partial side elevation and diagrammatically an inking mechanism constructed according to the invention. 75

Fig. 2 is a detail view.

In carrying the invention into effect as illustrated in Figs. 1 and 2 I provide a small motor *m* for independently operating the inking mechanism of the printing couples on each deck and for the purpose I mount on the motor shaft a worm gearing with a worm wheel *m'* mounted upon a vertical shaft *n* which serves through bevel wheel *n'* to impart movement to an intermediate shaft *f* carried in a bracket *f'* carried on the side frame of the machine. 80

The bevel wheel *n'* engages with a bevel wheel *l* mounted upon the intermediate shaft *f* and motion is communicated to the latter thereby in the direction of the arrow. The bevel wheel *l* is mounted so as to be operable only in one direction and to run free in the opposite direction. 90

On the intermediate shaft *f* a worm *g* is mounted engaging in a worm wheel *g'* mounted upon the shaft *h* as usually provided in printing presses and from which shaft movement is imparted to the ductor roller *k* and the ink duct roller *j* in the usual manner by means of a cam as indicated. 95

The intermediate shaft *f* also carries a bevel wheel *d'* which engages with a corresponding bevel wheel *d''* integrally provided and connected with the gear wheel *d* through which movement is imparted to the distributing drum *c* by means of the gear wheel *c'*. 105

The bevel wheel *d'* is mounted upon a bush *d''* and at one end protrudes beyond 110

the face of the bevel wheel d^1 , where it is provided with teeth or projections d^4 with which may engage pawls d^5 by which movement may be imparted if required to the shaft f and through the shaft f to the inking mechanism from the main drive of the press. A pawl d^6 may also be provided which may be brought from its disengaged position which is indicated in dotted lines 10 in Fig. 1^a into its engaged position so that thus the drive may be also transmitted from the motor m to the ink distributing drum cylinders and rollers. For this purpose spring blades d^7 are provided to contact 15 with flat faces provided upon the respective bosses of the pawls d^5 and d^6 at an angle of 90° one to the other so that thus the respective pawls may be held by the corresponding spring blade d^7 in or out of its engaged 20 position.

The distributing cylinder e has a gear wheel e^1 mounted upon its spindle for engaging with the gear wheel d and the gear wheel e^1 gears through an intermediate pinion b^1 with the gear wheel a^1 of the type cylinder a which is mounted in proximity to the impression cylinder i as indicated. The usual ink distributing cylinders r^1 are mounted so as to rotate upon the ink distributing cylinder e and the ink distributing drum e , while ink rollers r apply ink to the type cylinder a . These ink cylinders r may advantageously be so mounted that they may be readily lifted from contact with the 35 type cylinder a .

It will be understood that the respective parts of the ink mechanism move in the direction indicated by the arrows and that the type cylinder a is provided with a free 40 wheel device comprising a ratchet wheel a^2 and pawls a^3 by which no movement is communicated to it through the inking mechanism when the gear wheel a^1 of the type cylinder is rotated in the direction of the 45 arrow.

It will thus be understood that the ductor roller k and the ink duct roller j alone may be operated from the motor m at any desired speed and independently of the other 50 part of the inking mechanism or of the press, and that also the whole of the inking mechanism may be operated independently of the rest of the press, as for example, when it is desired to uniformly distribute the ink 55 before starting the press and so as to insure a proper application of ink upon the type cylinder at the very first impression.

Before starting under normal conditions there are no plates upon the type cylinder a 60 and therefore the inking rollers r will not be in contact with the surface of the cylinder a .

In Fig. 1 one half of the type cylinder is covered by a stereotype plate and in this position, while the cylinder a is stationary, 65 the ink distributing cylinder e with the dis-

tributing rollers r^1 may be freely rotated but should it be desired to operate the inking mechanism after the plates have been mounted upon the cylinder a , the inking rollers r may be lifted out of contact. If under this 70 condition the motor m is started the whole of the inking mechanism will be operated but owing to the gear wheel a^1 being mounted so that motion can be communicated to it only in one direction from the main drive, 75 no motion is communicated from the inking mechanism beyond the inking rollers r under operation of the motor m . The worm gear g , g^1 will also be set into motion on operation of the motor m and through it 80 the ductor roller k and the ink duct cylinder j will be operated in the usual way.

On the distribution of ink through the inking mechanism preparatory to starting of the press, the pawl of the toothed bevel wheel d^1 may be disengaged as a further disconnected operation of the distributing cylinders and rollers will not be required during the normal running and printing period. During this period the main part of 90 the inking mechanism will be driven in the normal manner and direction from the main drive through the gear wheel a^1 , and the duct cylinder j and ductor roller k will be driven from the motor m .

The controller of the motor m may be connected to the controller of the main driving motor of the press and may act in synchronism therewith. Thus supposing the first contact speed of the motor m be so ad-

justed that it will drive the intermediate shaft f at 25% of the mechanism speed adjustable by the whole press, then when the main motor controller is so positioned as to cause the starting of the press, the motor 100

starting contact for the small motor also closes its circuit and so starts the motor m and causes the rotation of the intermediate shaft f with the result that the ink fed will be the same as it will be when the corre-

sponding impression and type cylinders reach 25% of the running speed, as by the independent drive and the use of the free wheel at d^1 the intermediate shaft f is at first running faster and ahead of the main 110 mechanism. When the press attains the 25% of its maximum speed it will overtake the speed of the small motor m and on the speed of the press accelerating further it will drive back to the motor and increase the speed of

the motor also but owing to the free wheel interposed at l this cannot result and the motor m may if so adjusted be automatically cut out of action by the controller so as not again to be set into motion unless and

until the press drops down to 25% or whatever the speed at which it is desired to pick up.

By this means it will be found that the ink on the printing surface will be quite 130

full and black even at 2% of the full running speed.

The motor m may be provided with a variable speed regulator, whereby the motor speed and therefore the flow of ink may be instantly varied throughout the whole range of speeds while the press is running.

In printing presses as usually constructed for newspaper and similar work, a usual ratio of ink feed supply is approximately 4 to 1: that is, the ink feeding or ductor roller gives a fresh supply of ink once only for each four copies of the printed product of the press, and in many presses the difference is greater. Thus it will be understood that the supply of ink is never uniform in each of the four following copies but necessarily varies in each of the four from the maximum to a minimum amount. Upon the reduction of the speed of the press to half-speed the same variation in the application of ink results, but if the ink speed can be maintained at the maximum rate while the speed of the main or impressional part of the press is reduced to one-half, it is apparent that the ink supply may be increased up to the proportion of 1 to 2, that is, that the ink supply is so improved that one charge of ink is supplied for each two copies printed and that if the speed of the printing portion is still further reduced to one-quarter of full speed without altering the ink feed, then the ink feed will be so far increased that one charge of ink is supplied for each copy printed. Such a variation or increase in the ink feed may be provided according to the invention.

For art and similar rotary printing processes where the maximum density of color is required, the increase in the proportion of ink applied is also of especial advantage, and particularly when stopping and starting. It will further be understood that according to the invention this variation in the proportion of ink applied may be controlled from a single or multiple points. Furthermore, each deck unit may be operated separately by hand if so desired for preparatory work, as, for example, by the application of a hand-wheel or crank lever on the end of the spindle of the ink distributing drum c . Furthermore, by the use of the locking pin or pawl at d^1 , the whole of the inking mechanism may be put into operation from the hand-wheel or crank lever.

I claim:—

1. In inking mechanism for printing presses, ink supply mechanism comprising the fountain roller and the ductor roller, a motor by which these elements are operated independently of the press mechanism, mechanism by which the ink distributing drum and ink distributing rollers may be operated from the press and elements by which the fountain roller and ductor roller may be operated from the press on a predetermined speed being attained, substantially as described.
2. In inking mechanism for printing presses, ink supply mechanism comprising the fountain roller and ink duct roller, means for causing the operation of the said mechanism independently of the press mechanism by which the ink distributing drum is operated from the press and a free wheel connection between the mechanism of the press and the said ink supply mechanism, substantially as described.
3. In inking mechanism for printing presses, ink supply mechanism comprising the fountain roller and ductor roller, means for operating the said ink supply mechanism independently of the press and a free wheel device connecting the ink supply mechanism with the mechanism of the press to permit the alternative operation of the ink supply mechanism from the press or from the independent means employed for operating the ink supply mechanism, substantially as described.
4. In inking mechanism for printing presses, ink supply mechanism comprising the fountain roller and ductor roller, means for operating the said mechanism independently of the press, mechanism by which the ink distributing cylinder is operated from the press, and free wheel devices by which the said ink supply mechanism may be operated from the press on a determined speed being attained by the press, substantially as described.
5. In inking mechanism for printing presses, ink supply mechanism and ink distributing mechanism and a free wheel device between the said ink supply mechanism and said ink distributing mechanism, substantially as described.
6. In inking mechanism for printing presses, ink supply mechanism and ink distributing mechanism, a free wheel device between the said ink supply mechanism and said ink distributing mechanism, a motor for the operation of the said ink supply mechanism independently of the press, and a free wheel device between the said ink supply mechanism and the said motor, substantially as described.
7. In inking mechanism for printing presses, ink supply mechanism comprising the fountain roller and ductor roller and ink distributing mechanism comprising the ink distributing drum, a free wheel connection between the said ink distributing mechanism and the press to permit of the said ink distributing mechanism being operated independently of the press, means for operating the ink supply mechanism independently of the press, and means for alternatively causing the operation of the ink distributing mechanism from the ink supply

mechanism or from the mechanism of the press, substantially as described.

8. Inking mechanism for printing presses, consisting of ink supply mechanism comprising a motor, a free wheel device between the motor and the ink supply mechanism, a worm and worm wheel device for causing the operation of the ductor roller, the said ductor roller ink distributing mechanism comprising the ink distributing drum and a free

wheel device between the said ink distributing mechanism and the type cylinder, and a free wheel connection between the ink distributing mechanism and the ink supply mechanism, substantially as described.

GEO. W. MASCORD.
